UNITED STATES PATENT OFFICE.

HAROLD EDWARD WHITE, OF PUTNEY, LONDON, ENGLAND, ASSIGNOR TO THE AEOLIAN COMPANY, OF NEW YORK, N. Y., A CORPORATION OF CONNECTICUT.

TONE-MODIFIER.

1,304,005.

Specification of Letters Patent. Patented May 20, 1919.

Application filed June 7, 1916. Serial No. 102,262.

To all whom it may concern:

Be it known that I, HAROLD EDWARD WHITE, a subject of the King of Great Britain, residing at 11 Gamlen Road, Putney, in the county of London, England, have invented certain new and useful Improvements in Tone-Modifiers, of which the following is a specification.

This invention relates to gramophones, phonographs and similar sound reproducing instruments, the chief object being to enable the volume of sound emitted by the instrument to be varied and controlled in a more reliable and effective manner than has heretofore been possible.

According to the invention a pneumatic or hydraulic sound modifying appliance for the gramophone or similar sound reproducing instrument is provided and adapted to be controlled so as to vary the volume of sound emitted by the instrument. The sound modifying appliance preferably comprises a flexible chamber situated at some point between the sound box and the mouth of the instrument and adapted to be expanded or contracted at the will of the operator by pneumatic or hydraulic means so as to vary the opening for the passage of the sound.

Alternatively the sound modifying appliance may be of any other suitable type, for example, it may comprise a valve, plug, disk or other obturating device, arranged between the sound box and the mouth of the instrument and operatively connected with a flexible bulb, bellows, air container or other pneumatic or hydraulic pressure producing means so as to be actuated by the air or liquid pressure produced thereby, such flexible bulb or other means being controlled by the operator or by the driving mechanism of the gramophone, phonograph or other sound reproducing instrument.

In order that the said invention may be clearly understood and readily carried into effect the same will now be described more fully with reference to the accompanying diagrammatic drawings in which—

Figure 1 is a sectional elevation of the recording instrument in the form of a gramophone showing the improved sound modifying device applied thereto.

Fig. 2 is a sectional elevation of one form of the improved sound modifying appliance.

Fig. 3 is a cross sectional view thereof taken on the line 3—3 of Fig. 2.

Fig. 4 is a sectional elevation of a modified form of the sound modifying appliance, and

Fig. 5 is a cross sectional view thereof.

Figs. 6 to 9 inclusive show various forms of pressure producing means employed with the appliance.

Figs. 10 to 13 inclusive are detail views of valves adapted to control or sustain the action of the sound modifying appliance.

Fig. 14 is a sectional elevation of a portion of a horn for use with the reproducing instrument showing a further modification in the improved sound modifying appliance applied thereto.

Referring to Figs. 1 to 3 the sound modifying appliance comprises a rigid or semi-rigid throat *a* provided with a flexible airtight lining *a'* which is adapted to be expanded at will to vary the extent of the opening *a²* in the throat available for the passage of the sound by means of air or liquid pressure (hereinafter called fluid pressure) derived from a flexible bulb, bellows, air container or other pneumatic pressure producing means actuated by the operator or by the driving mechanism of the instrument. The flexible lining *a'* is sealed at its ends *a³* *a⁴* to the inside of the throat *a* so as to normally lie close thereto, as shown in full lines in Figs. 2 and 3, and leave a free opening *a²* in the throat for the passage of the sound. An annular chamber *a⁵* thus exists between the lining and the inside of the throat and if air or liquid (hereinafter called fluid) is forced into this chamber the lining will be expanded or dilated, as shown in broken lines, to partially or wholly close the passage through the throat. Fluid pressure may be derived from a flexible bulb *b*, Figs. 1 and 7, which is connected by a flexible tube *b'* to a tube *b²* leading to the annular chamber *a⁵* between the lining *a'* and the throat *a* of the appliance. The tube *b²* is connected to the flexible lining *a'* which forms within the throat *a* an expansible sleeve adapted to be inflated or deflated at will. The degree of closing will depend upon the volume of fluid forced into the annular chamber through the flexible tube *b'*.

The operator may, by compressing the bulb *b*, produce any desired modification of the

sound emitted by the instrument. The form that the lining a' would assume when fully expanded may be governed by a spider a^6 or suitable partitions arranged centrally in 5 the passage in the throat a . With this arrangement, when fluid is forced through pipe b^2 into the chamber a^5 , the lining a' which normally rests against the inner wall 10 of the throat a , as shown in full lines in Figs. 2 and 3, is forced inwardly or, in other words, away from the wall of the throat a , and, when in fully expanded condition, it rests against the said spider or partitions 15 and assumes a definite configuration, as shown in broken lines in Figs. 2 and 3. The same result may be obtained by forming suitable fold lines on the lining which would insure the same folding into a predetermined number of sections when it was dilated by the fluid pressure in the annular 20 space a^5 .

The connecting tube b' may be made of any suitable length and if desired long enough for remote control. Or the bulb b 25 may be arranged within the instrument and be operated by a compressing mechanism suitably controlled by the operator through the intervention of a Bowden wire or other power transmitting device. Such an arrangement is shown in Fig. 6 where the bulb or flexible container b is arranged between two boards or members d , d' the latter of which is hinged or pivoted to the member d , so as to be capable of angular movement 30 to force the fluid through the tube d^2 into the annular chamber between the flexible lining and the throat of the sound modifying appliance. The member d' is moved inwardly about its pivot or hinge against the 35 action of a spring d^3 which normally tends to retain the bulb or flexible container b in the expanded condition. Motion is imparted to the member d' by a rod d^4 which is connected at one end to a link d^5 carried 40 by the said member and at the other end to the inner or actuating wire d^6 of a Bowden connection d^7 . The outer end of the wire d^6 is connected to a plunger or rod d^8 displaceably mounted in a cylinder d^9 , the latter being provided with finger grips d^{10} to facilitate the manipulation of the device. When the plunger d^{10} is withdrawn from the cylinder d^9 , the member d' is angularly displaced to compress the bulb or flexible 50 container and thereby expand or dilate the lining of the sound modifying device. If the plunger is released after being withdrawn in this manner it will return to its original position under the action of the 55 spring d^3 and the lining of the sound modifying device will regain its inoperative position. The bulb b may be replaced by any suitable pressure producing means such as the pump e or bellows f shown respectively 60 in Figs. 8 and 9. The pump e comprises a

cylinder e' which is provided with a piston e^2 adapted to be displaced therein against the action of a spring e^3 by a rod e^4 which projects through the end of the cylinder. The spring e^3 normally retains the piston 70 e^2 at the left hand end of the cylinder so that the lining of the sound modifying appliance is not affected. When the piston is forced along the cylinder against the action of the spring the fluid will be forced 75 through the tube e^5 connected to the annular chamber between the lining and the throat of the sound modifying appliance.

The bellows f shown in Fig. 9 is normally held in the expanded condition by a spring 80 f' suitably disposed therein, and is connected to the annular chamber of the sound modifying appliance by means of the tube f^2 so as to operate in a similar manner to the pressure producing means hereinbefore 85 described.

The volume of fluid forced into the annular chamber of the throat may be controlled by a valve g shown in Figs. 10 and 11 which is arranged between the pressure producing 90 means and the sound modifying appliance. This valve is adapted to be set to vary the dimensions of an orifice or passage g' through which the fluid passes and thereby 95 regulates the time during which the action of the sound modifying appliance endures.

Any other form of screw down or reducing valve may however be employed.

If the partial or complete dilation or expansion of the flexible lining is to be sustained a valve or other obturating device such as that shown in Figs. 12 and 13 may be arranged between the pressure producing means and the annular fluid chamber of the sound modifying appliance so that by 100 suitably operating the same the pressure in the said chamber will be maintained for the desired period of time. The valve comprises a plug k which is adapted to be turned to obstruct the passage k' through 105 which the fluid passes on its way to the sound modifying appliance.

It will be understood that either of the aforesaid valves may be employed singly to moderate or sustain the pressure applied to 110 the sound modifying appliance.

The aforesaid flexible lining in the sound modifying appliance may be replaced by the airtight pouch m shown in Figs. 4 and 5. This member is of a flexible character and 115 is vertically arranged diametrically across the interior of the throat a and adapted to be expanded by internal fluid pressure to control the extent of the opening therein. The dilation of the pouch would be effected 120 in a similar manner to the lining by means of a flexible bulb, bellows, air container or other pressure producing means actuated by the operator or by the driving mechanism of the instrument. The pouch however will 125

expand outwardly toward the interior surface of the throat a to assume the position shown in broken lines in Figs. 4 and 5, as distinguished from the lining which expands inwardly toward the central axis of the passage through the throat. In the former case the closure would be made between the pouch and the internal surface of the throat while in the latter case the closure would be made between the outer surfaces of the different sections and the surface of the centrally disposed spider or partitions. If desired the inner wall of the throat a may be provided with an annular protuberance m' so as to insure a more perfect closure between the same and the pouch m . Fluid is conducted to the interior of the pouch m through the tube m' which is suitably connected with the pressure producing means hereinbefore described.

The throat a may be made of rubber, leather, felt, papier-mâché, or other suitable material and may be arranged as shown in Fig. 1, between the sound box n and the mouth of the horn n' of the instrument.

Referring to Fig. 14 a is the gramophone horn of an instrument provided with a sound modifying appliance a' comprising a flexible throat a^3 which is adapted to be closed by a plug or stopper a^9 mounted on a spindle or rod a^{10} which is capable of axial displacement. Movement is imparted to the rod a^{10} by a bellows a^{11} which is expanded by fluid pressure derived from a flexible bulb operatively connected with the inflatable or collapsible member c^2 thereof by means of a flexible tube b' .

The lower end of the rod a^{10} is connected to a link a^{12} carried by the displaceable member or board a' of the bellows so that axial movement is imparted to the said rod when

the member d' is angularly displaced around its pivot or hinge by the inflation or deflation of the member c^2 .

What I claim and desire to secure by Letters Patent of the United States is:—

1. In combination, a sound-conveying conduit; sound-modifier means comprising an expandable annular chamber within said conduit; and fluid-control means for at will expanding said chamber inwardly toward the axis of the conduit so as to vary the effective passage-way through said conduit. 50

2. In combination, a sound-conveying conduit; sound-modifier means comprising an expandable annular chamber within said conduit; fluid-control means for at will expanding said chamber inwardly toward the axis of the conduit so as to vary the effective passage-way through said conduit; and central means in the conduit governing the form which the inside of the annular chamber assumes when expanded against said means. 60

3. In combination, a sound-conveying conduit; and sound-modifier means for controlling the size of the passage-way through said conduit comprising an expandable chamber with connected fluid-control means for at will varying the degree of expansion of said chamber, and valve-means for at will shutting off said connection between the expandable chamber and the fluid-control means. 65

4. In combination, a sound-conveying conduit; and sound-modifier means for controlling the size of the passage-way through said conduit comprising a valve in said conduit, an expandable chamber operatively connected with said valve, and a fluid-control means connected with said chamber for at will varying the degree of expansion of said chamber. 75 80

HAROLD EDWARD WHITE.
